UNITED STATES PATENT OFFICE.

MONROE M. SCHWARZSCHILD AND BELLE SCHEUER, OF NEW YORK, N. Y.

TYPE-WRITING-DOLL TOY.

1,160,457.

Specification of Letters Patent. Patented Nov. 16, 1915.

Application filed August 28, 1915. Serial No. 47,751.

To all whom it may concern:

Be it known that we, MONROE M. SCHWARZSCHILD and BELLE SCHEUER, citizens of the United States, residing at New York, in the county of New York and State of New York, have invented certain new and useful Improvements in Type-Writing-Doll Toys; and we do hereby declare the following to be a full, clear, and exact description 10 of the invention, such as will enable others skilled in the art to which it appertains to make and use the same.

Our invention consists in the novel features hereinafter described reference being 15 had to the accompanying drawings which show one embodiment of our invention selected by us for purposes of illustration, and a slight modification thereof, and said invention is fully disclosed in the following 20 description and claims.

Referring to the said drawings: Figure 1 is a perspective view of an embodiment of our invention comprising a typewriting doll toy complete with the doll or figure supported in operative relation with the other parts of the apparatus. Fig. 2 represents a vertical transverse sectional view of the toy, the doll or figure being shown in elevation. Fig. 3 represents a horizontal sectional view of the apparatus, the doll or figure being removed and the supporting part therefor being broken away. Fig. 4 is a vertical longitudinal sectional view of the apparatus. Fig. 5 is a horizontal sectional view similar to Fig. 3 of a slightly modified form of the apparatus in which it is operated automatically by a spring motor, or clock mechanism.

The object of our invention is to produce 40 a typewriting doll toy comprising among its members a part constructed to simulate a typewriting machine, and preferably supported upon a part constructed to give the appearance of a typewriter desk or stand, 45 in conjunction with a doll or figure, the arms of which extend over the keyboard portion of the typewriter part and are operated by mechanical means of any kind, either by hand or by a suitable spring motor, or clock mechanism so as to give the 50 appearance of operating the typewriter keys, and further to provide mechanically operated printing mechanism including a type roller, a paper supporting and feeding 55 roller and inking means for the type roller, operated simultaneously with the arms of

the doll or figure, so that letters, words or a complete letter may be printed upon a strip of paper which is fed through and may be drawn from the machine.

Our invention also contemplates provision for changing the letters, words or sentences printed either by providing for the removal of the printing roller and the substitution of another containing different type, or by 65 providing the roller with removable type which may be readily changed, or otherwise.

Our invention also contemplates the provision of noise producing mechanism to simulate the tapping or clicking sound of 70 a typewriting machine, a bell and other details of construction and combination of parts hereinafter fully described, the whole producing an amusing, interesting and instructive toy for children.

The device can also be used, if desired, for advertising or any other purposes for which it may be found to be adapted.

The figure, as hereinafter described, may be permanently secured to or formed with 80 other parts of the device, or it may be detachable and in such case the apparatus is so constructed that the figure, which may be a special figure or any suitable doll or figure of the proper size can be detachably 85 supported in operative relation to the other parts of the apparatus and similarly connected to the arm operating mechanism.

We do not desire to be limited to the exact 90 details of construction hereinafter described as the same may be varied by skilled mechanics in constructing the device in various forms and sizes for the market without departing from the invention.

In the embodiment of our invention selected by us for purposes of illustration and shown in the accompanying drawings, 1 represents a part constructed to simulate a typewriting machine and preferably having combined therewith a supporting part 100 formed to represent a typewriting desk or stand upon which the machine is mounted as indicated at 2. These parts may be constructed of wood, sheet metal, or any other suitable material and it is only necessary 105 that they shall have an outward appearance suggestive of a typewriting machine and stand, many of the detail parts being merely indicated more or less realistically. For example, we ordinarily indicate the key-board by painting circular portions upon a flat surface as indicated at 3, and the

drawers of the desk can be painted on the exterior of the front face. More elaborate and expensive embodiments of the device may represent these parts more realistically, if desired.

5 4 represents a support for a doll or figure which simulates the appearance of a chair or stool, and 5 represents the doll or figure provided with movable arms, 6, which extend toward and over the key-board portion. The doll or figure, and in some cases the support therefor may be formed integrally with or be rigidly secured to the desk portion 2, and the arms may be actuated in any 10 desired manner, but we prefer to actuate the arms by means of vertical rods, 7, extending through apertures in the key-board part, 3, and having their lower ends connected to actuating arms or cranks, 8, 8, on a rock shaft or crank shaft, 9, which extends longitudinally through the desk portion, 2, and is mounted in suitable bearings, said shaft being operated as hereinafter described, or in any desired manner to cause the arms of 15 the doll or figure to rise and fall above the key-board portion 3. In this instance the shaft, 9, is arranged to rock, and is moved in one direction by an arm 10^a secured to a driving shaft, 10, mounted in the desk portion, 2, and operated by hand by a crank, 10^b, (or by a spring motor or clock mechanism as hereinafter described), the said arm 10^a engaging an arm, 9^a, on the shaft, 9, to rock the shaft, 9, in one direction, said shaft 20 being rocked in the opposite direction by a spring, 9^b. A stop 9^d on the casing engages the arm 9^a and limits the movement of the rock shaft under the pull of the spring as clearly shown in Figs. 3, 4 and 5. In this instance 25 the back of the doll support, 4, is provided with a fork shaped clip, 11, to engage a headed stud or button, 12, on the doll or figure to hold it detachably in position and a similar clip, 13, is provided at the outer end of each 30 of the movable arms, to detachably connect them to the upper ends of the vertical actuating rods, 7, which are in this instance provided with enlarged heads, 14, but any other detachable connecting means may be employed, and as before stated the doll may be 35 permanently secured in position and permanently connected to the arm actuating devices, if desired. Obviously any ordinary doll of proper size may be supplied with 40 clips, 13, and button, 12, or the doll or figure may be furnished with the apparatus.

The typewriter part, 1, is provided with a paper support preferably in the form of a roller, 23, and with paper guides, 24, 24, 45 adjacent thereto, and we prefer to simulate the typewriting ribbon and its spools by means of two cylindrical parts, 21, connected by a bar, 20, preferably formed of sheet metal, and to employ in connection therewith a movable key or tappet, 19, which by

striking on the metallic ribbon piece or bar, 20, produces a tapping or clicking sound to simulate typing. In this instance the tappet or key, 19, is at the upper end of a lever, 16, pivoted at, 17, and having its upper end, 70 in position to be struck by an arm, 9^c, on the rock shaft, 9. We do not limit ourselves, however, to this particular form of sound producing device. The lower end 18 of the lever is so disposed that it is inclined to the 75 vertical when the tappet 19 is in contact with the ribbon plate, 20, so that the action of gravity on the part 18 tends to move the tappet away from the ribbon plate, and it is forcibly moved toward the ribbon plate 80 by the arm 9^c as before stated. We also preferably provide a bell indicated at 26, mounted with the desk part, 2, and adapted to be struck by a striker arm, 27, secured to the rock shaft, 9, as shown. 85

We also provide printing mechanism for printing on a strip or sheet of paper which is passed around the paper supporting and feeding roller, 23, as indicated at 30 in Fig. 2. For this purpose, we prefer to employ a 90 removable printing roller, 31, the trunnions, 32, of which engage horizontal slots, 33, in the side walls of the desk part, 2, and are held at the inner ends of the said slots in any suitable manner, in this instance, by the detachable pins, 34, engaging guides on said side walls. The roller, 31, is provided with a series of letters, words, sentences, etc., and preferably they are arranged in the form of a letter or communication, although the particular matter to be printed is not essential. The type, which will ordinarily be of rubber may be permanently secured to the roller, in which case the roller may be removed and replaced by another roller having different 95 words, etc. or the type may be detachably connected to the roller, and may be changed and reset at will according to any of the well known methods of applying rubber type or letters, or words, etc., to a supporting and 100 printing roller. 105

In the embodiment of our invention herein shown, the type or printing roller, 31, is driven by means of a gear, 35, connected therewith and meshing with a pinion, 36, on the driving shaft, 10, and the type roller is preferably provided at each end with a friction surface, 37, which engages the paper supporting roller, 23, or the sheet of paper between said rollers, to feed the paper and 110 cause the rotation of the paper roll, 23.

Any suitable means may be provided for inking the type roller. In this instance, we have shown an inking roller, 38, mounted below the printing roller, and of such a 115 length as to engage the type between the friction faces, 37, and an inking pad or reservoir, 39, frictionally engaging the inking roller and distributing ink over the surface thereof. We prefer to provide the desk 120

portion, 2, with a hinged rear wall, 50, as shown, held in position by a suitable lock or catch, 51, which can be thrown back to permit the removal and replacing of the type roller, and the renewal of the ink supply to the ink pad or reservoir.

It will be seen that by inserting a strip or sheet of paper under the roller, 23, and between it and the inking roller and rotating the driving shaft, as by turning the crank, 10^b, the arms of the doll will be caused to move up and down over the key-board, accompanied by the clicking sound produced by the tappet, 19, and by the ringing of the bell, and the type roller or printing roller will print upon the paper the characters thereon, and preferably a complete letter, which can be read in full as soon as the printing roller has made a complete revolution. Variations in the matter to be set up or provided upon the type or printing roll may be made as previously indicated and the device forms an interesting and instructive toy and may also be made up for advertising or other purposes.

In Fig. 5, we have shown a modification of the device in which a motor, in this instance a spring motor or clock mechanism, 40, is shown provided with a gear wheel, 41, which meshes with the gear, 35, on the printing roll shaft and drives the printing roller, the shaft, 10, (which in this instance is not provided with a hand operating device) and the rock shaft, 9, the parts being otherwise identical with those heretofore described. The spring motor (or clock mechanism) 40, is provided with the usual winding key, 42, and escapement or retarding device, 43, for retarding the action of the spring in unwinding. The particular form of spring (or other) motor employed forms no part of our invention and it need not be more particularly described.

What we claim and desire to secure by Letters Patent is:

1. In a typewriting doll toy, the combination with a part constructed to simulate a typewriting machine and its support, and provided with a passage for a sheet of paper, a printing roller, means for supporting a sheet of paper adjacent to said roller and feeding it through the passage of the typewriter part, and operating means for said printing roller, and paper feeding means whereby the characters printed on the paper are given the appearance of having been printed by the type-writing machine part.

2. In a typewriting doll toy, the combination with parts constructed to simulate a typewriting machine, of a paper supporting roller, a printing roller, movable arm actuating devices, a doll supported adjacent to the typewriting machine and provided with movable arms, operatively connected with said arm actuating devices, and means for

operating said rollers and arms actuating devices.

3. In a typewriting doll toy, the combination with a part constructed to simulate the body of a typewriting machine, of a paper supporting and feeding roller mounted rotatably therein, and arranged to simulate the paper roller of the typewriter, a printing roller mounted in operative relation to said paper roller, for printing characters on the paper carried thereby, and means for operating said printing roller and paper roller, whereby the characters printed on the paper are given the appearance of having been printed by the typewriting machine part.

4. In a typewriting doll toy, the combination with parts constructed to simulate a typewriting machine, of a doll provided with movable arms extending over the key-board thereof, arm actuating devices, a paper supporting roller, a removable printing roller, and operating means for said rollers, and arm actuating devices, whereby the printing roller can be removed to change the characters to be printed on the paper.

5. In a typewriting doll toy, the combination with parts constructed to simulate a typewriting machine, of a doll provided with movable arms extending over the key-board thereof, arm actuating devices, a paper supporting roller, a removable printing roller, having portions in frictional contact therewith, an inking roller in frictional contact with the type portion of the printing roller, and means for operating one of said rollers and the arm actuating devices.

6. In a typewriting doll toy the combination with a part constructed to simulate a typewriting machine, a striker plate supported adjacent thereto, a doll having movable arms extending above the key-board portion of the typewriting machine part, a tappet adapted to engage the striker plate, and means for operating the arm actuating devices and said tappet.

7. In a typewriting doll toy, the combination with a part constructed to simulate a typewriting machine, a striker plate, supported adjacent thereto, a doll having movable arms extending above the key-board portion of the typewriting machine part, a tappet adapted to engage the striker plate, means for supporting and feeding a sheet of paper, printing mechanism, and means for operating said printing and paper feeding means, and said arm actuating devices and tappet.

8. In a typewriting doll toy, the combination with parts constructed to simulate a typewriting machine and supporting desk therefor, said desk part being provided with slotted portions, a paper roller mounted in the typewriting machine part, a removable printing roller mounted in the desk part and having its shaft engaging said slots,

locking devices for holding said shaft in said slots, a doll provided with movable arms extending over the key-board portion of the typewriting machine part, arm actuating devices, and means for operating said arm actuating devices and said rollers.

9. In a typewriting doll toy, the combination with a part constructed to simulate a typewriting machine, of a doll having movable arms, extending above the key-board thereof, arm actuating rods, a rock shaft, arms on said rock shaft operatively connected with said rods, and means for operating said rock shaft.

10. In a typewriting doll toy, the combination with a part constructed to simulate a typewriting machine, of a doll having movable arms, extending above the key-board thereof, arm actuating rods, a rock shaft, arms on said rock shaft operatively connected with said rods, a striker plate, a movable tappet having a part adjacent to said rock shaft, an arm on said rock shaft for operatively engaging said tappet, and means for operating said rock shaft.

11. In a typewriting doll toy, the combination with a part constructed to simulate a

typewriting machine, of a doll having movable arms, extending above the key-board thereof, arm actuating rods, a rock shaft, 30 arms on said rock shaft operatively connected with said rods, a paper supporting roller, a printing roller, and operating means for simultaneously operating said rollers and said rock shaft.

12. In a typewriting doll toy, the combination with a part constructed to simulate a typewriting machine, of a doll having movable arms, extending above the key-board thereof, arm actuating rods, a rock 40 shaft, arms on said rock shaft operatively connected with said rods, a paper supporting roller, a printing roller, a rotary driving device operatively connected to drive said rollers, an actuating arm on said rotary device for actuating said rock shaft, an arm on said rock shaft to engage said actuating arm, and a spring connected to said rock shaft.

In testimony whereof we affix our signatures. 50

MONROE M. SCHWARZSCHILD.
BELLE SCHEUER.
